UNITED STATES PATENT OFFICE.

PAUL H. GRIMM, OF GLEN COVE, NEW YORK, ASSIGNOR OF ONE-HALF
TO JOHN DURYEA, OF SAME PLACE.

INJECTOR-BLOWER.

SPECIFICATION forming part of Letters Patent No. 282,074, dated July 31, 1883.

Application filed May 3, 1883. (Model.)

To all whom it may concern:

Be it known that I, PAUL H. GRIMM, a citizen of the United States, residing at Glen Cove, in the county of Queens and State of New York, have invented certain new and useful Improvements in Injector-Blowers, of which the following is a specification, reference being had therein to the accompanying drawings.

My invention relates to the construction of an injector-blower or exhaust wherein a column of air or gas is propelled or projected by the pressure of jets of steam or compressed air; and its object is to force or project a current of air in a given direction with as little expenditure of steam-power and with as little admixture of steam with the air or gas as practicable.

The novel features of my invention will be hereinafter described and claimed.

In the drawings, Figure 1 is a side elevation 20 of my device. Fig. 2 is a sectional elevation, and Fig. 3 is a detail.

A represents the casing of my air-injector. This casing is preferably cast in one piece for convenience of construction. The casing has 25 a bell-mouthing air-inlet, *a*, a bell-mouthing outlet-passage, *b*, and a combining-chamber, *c*, between the narrowed portions *d d'* of the casing.

Surrounding the casing, at about the middle in the construction shown, there is an annular 30 chamber, *e*. The steam in the annular chamber *e* should be as nearly at boiler-pressure as possible. This may be maintained by leaving the pipe *l*, which connects to the boiler, quite unobstructed, and by making said pipe of sufficient 35 size.

A series of nozzles or jet-pipes, *f*, are placed in the bottom of chamber *e*. These pipes or nozzles incline toward the center of the combining-chamber *c*, as shown in Fig. 2, and any suitable 40 number may be employed. They should be arranged at equal distances, so as to entirely surround the combining-chamber *c*. I have found six of these jet-nozzles to serve a good purpose, but do not limit myself to that number. Each 45 nozzle is provided with a valve, *i*, which may be raised and lowered by means of screw-shaft *g*, which works steam-tight in stuffing-box *k*. This box may screw into the upper part of the steam-chamber *e*, as at *l l'*, Fig. 2. Other suit-

able and convenient modes of operating the 50 valves with relation to the nozzles may be used.

The valves *i* are conical, and can be screwed down steam-tight into the conical valve-seats of the nozzles *f*.

My improved injector-blower is adapted for 55 any of the uses for which the fan-blower has been designed—as, for instance, the conveyance of an air-blast to a furnace, the exhaust of gas from mines, the ventilation of buildings or ships, the propulsion of grain, feed, shavings, &c., in 60 a chute or conveyer, and for other purposes.

The mode of operation is as follows: The blower is placed with the bell-mouth *b* in proximity to the furnace or other place into which it is desired to introduce a current of air. Steam 65 being admitted to chamber *e*, preferably at high pressure, the valves *i* are opened and steam rushes through the nozzles *f* toward the center of the combining-chamber *c*. This inrush of steam causes a rapid inflow of air through the 70 bell-mouthing passage *a* and into the chamber *c*, where air and steam are intimately mixed. The compression of the mixed air and steam as it passes through the narrowed throat *d'* causes 75 it to flow outward through the bell-mouth *b* with increased velocity. By means of the valves *i*, operated by valve-rods *g*, as shown, the nozzles *f* may be opened more or less to regulate the flow of steam through said nozzles.

The valves on one side may be opened more than 80 those on the other to give the blast a definite direction; or the alternate valves may be opened different distances, so that steam may flow freely through one set of ports and be “wire-drawn” 85 through another set, thus producing an intimate commingling of the steam and air by reason of cross-currents and different velocities. The enlarged area of the combining-chamber gives space for the admixture of the steam from the jets with the inrushing air-currents, 90 while the inclination of the jet-pipes toward the center of this chamber gives such direction to the impinging currents as will cause them to move rapidly through the outflow-orifice.

It is apparent that the device may be operated by the introduction of compressed air into the chamber *e* instead of steam, so that the device would become entirely an air-injector. 95

The peculiar form of the bell-mouthed out-flow-pipes, with the intermediate combining-chamber of greater sectional area than the out-flow-tube, gives great advantage to this form 5 of injector-blower, the friction of passing currents on the tube being slight.

What I claim is—

1. An air-injector consisting, essentially, of an inflow-pipe, a bell-mouthed outflow-pipe, 10 an enlarged intervening combining-chamber, jet-nozzles leading into the combining-chamber, and independent means for closing each of said nozzles, substantially as described.

2. The combination, with the inflow and out-flow pipes, the intermediate combining-chamber, and the annular steam-chamber, of a series 15 of steam-jet nozzles, as *f*, arranged at approximately equal distances apart in the steam-chamber, and inclined toward the center of the combining-chamber, substantially as shown.

3. The combination, with the injector-pipe having bell-mouthed ends, as *a b*, and intermediate combining-chamber, of the annular steam-chamber and the steam-nozzles, as *f*, 20 leading from the steam-chamber to the combining-chamber, each nozzle having an adjustable valve, all constructed and arranged substantially as stated.

4. The air-injector casing, constructed substantially as described, having bell-mouthed 30 ends and enlarged central combining-chamber, the annular steam-chamber surrounding said casing and integral therewith, the series of inclined jet-nozzles leading from the steam-chamber, and the series of valves, one for each nozzle, having screw-threaded stems which pass through the steam-chamber, and may be operated from the outside to open or close the jet-nozzles, all in combination, substantially as stated. 35

5. The method of producing air-currents, which consists in drawing a column of air into a tube by means of controllable separate steam-jets forced into said tube in an inclined direction, permitting the steam and air to expand 40 and mix in a chamber of enlarged area, and then forcing out the mixed current through a reduced aperture, substantially as described. 45

In testimony whereof I affix my signature in presence of two witnesses.

PAUL H. GRIMM.
